CLAIM

The ornamental design for a base for a container, as shown and described.

DESCRIPTION

FIG. 1 illustrates a perspective view of base for a container showing our new design;

FIG. 2 illustrates a top perspective view thereof;

FIG. 3 illustrates a bottom perspective view thereof;

FIG. 4 illustrates a left side elevational view thereof, the right side elevational view being a mirror image;

FIG. 5 illustrates a front elevational view thereof, the rear elevational view being a mirror image;

FIG. 6 illustrates a top plan view thereof;

FIG. 7 illustrates a bottom plan view thereof; and,

FIG. 8 illustrates a cross-sectional view thereof taken from FIG. 6.

The broken lines showing the can are for illustrative purposes only and form no part of the claimed design.

1 Claim, 4 Drawing Sheets
